CLAIM

The ornamental design for a dental flosser, substantially as shown and described.

DESCRIPTION

FIG. 1 is an isometric view of a dental flosser showing my new design;

FIG. 2 is an elevation view showing one end thereof;
FIG. 3 is an elevation view showing the other end thereof;

FIG. 4 is a side elevation view thereof;

FIG. 5 is a side elevation view similar to FIG. 4 and showing an alternate embodiment thereof; and

FIG. 6 is an end elevation view similar to FIG. 2 and showing the alternate embodiment.

FIG.1

FIG.2

FIG.3

FIG.4

FIG.6
